UNITED STATES PATENT OFFICE.

ARTHUR M. SIDENBERG, OF NEW YORK, N. Y., ASSIGNOR TO ATLANTIC COMB WORKS,
A CORPORATION OF NEW YORK.

DESIGN FOR A BACK FOR A MIRROR, BRUSH, OR SIMILAR ARTICLE.

56,711.

Specification for Design.

Patented Nov. 30, 1920.

Application filed February 17, 1920. Serial No. 359,347. Term of patent 7 years.

To all whom it may concern:

Be it known that I, ARTHUR M. SIDENBERG, a citizen of the United States, residing at the city of New York, in the county and State of New York, have invented a new, original, and ornamental Design for a Back for a Mirror, Brush, or Similar Article, of which the following is a specification, reference being had to the accompanying drawing, forming part thereof.

The figure is a plan view of a mirror, showing my new design.

I claim:

The ornamental design for a back for a mirror, brush, or similar article, as shown.

ARTHUR M. SIDENBERG.

Witness:

MORRIS H. ADLER.
